(57) **CLAIM**

The ornamental design for a bed tray rim, as shown and described.

DESCRIPTION

FIG. 1 is a left, elevated, quartering perspective view of the new design for the bed tray rim of the present invention. FIG. 2 is a left side elevational view of the bed tray rim shown in FIG. 1, the right side elevational view being a mirror image thereof.

FIG. 3 is a front elevational view of the bed tray rim shown in FIG. 1;

FIG. 4 is a top plan view of the bed tray rim shown in FIG. 1;

FIG. 5 is a bottom plan view of the bed tray rim shown in FIG. 1; and,

FIG. 6 is a section view as taken in FIG. 4 and showing a rear elevational view of the bed tray rim of FIG. 1.

The broken lines included within the drawing figures depict environmental subject matter only and form no part of the claimed design.
